(57) **CLAIM**

The ornamental design for a firearm as shown and described.

DESCRIPTION

1. Firearm

1.1 is a front and perspective view of a firearm. 1.2 is a back perspective view of the firearm shown in 1.1. 1.3 is a right view of the firearm shown in 1.1. 1.4 is a left view of the firearm shown in 1.1. 1.5 is an enlarged front view of the firearm shown in 1.1. 1.6 is an enlarged back view of the firearm shown in 1.1. 1.7 is a top view of the firearm shown in 1.1. 1.8 is a bottom view of the firearm shown in 1.1. The broken lines depict portions of the firearm that form no part of the claimed design.

1 Claim, 8 Drawing Sheets
